UNITED STATES PATENT OFFICE.

SIGOURNEY WALES, OF CAMBRIDGE, MASSACHUSETTS, ASSIGNOR TO
WILLIAM C. HOWARD, OF NEW YORK COUNTY, NEW YORK.

RAZOR-STROP.

SPECIFICATION forming part of Letters Patent No. 281,419, dated July 17, 1883.

Application filed May 19, 1883. (No model.)

To all whom it may concern:

Be it known that I, SIGOURNEY WALES, of Cambridge, in the county of Middlesex and State of Massachusetts, have invented certain 5 new and useful Improvements in Razor-Strops, of which the following, taken in connection with the accompanying drawings, is a specification.

My invention relates to that class of razor-10 strops in which a soft leather strap strained between two bearing-points is used, and has for its object an improvement in the utility of the strop by increasing the number of working-surfaces, as well as an improvement in the 15 mechanism for straining the leather strap; and it consists in certain novel constructions and arrangements of parts, which will be readily understood by reference to the description of the drawings and to the claims to be herein-20 after given.

Figure 1 of the drawings is a perspective view, illustrating a longitudinal section of a three-sided strop with my improvements applied thereto. Fig. 2 is a transverse section of the same. Fig. 3 is a transverse section of a flat strop having two parallel working-faces. Fig. 4 is a similar section of a square strop having four working sides, two of which are leather and the other two hone surfaces, with the 30 addition of two detachable hone-surfaces. Fig. 5 is a perspective view of a strop having two hone-surfaces and two leather surfaces and two receptacles for razors or other articles, and Fig. 6 is a transverse section of the 35 same. Fig. 7 is a perspective view of the removable tablet, and Fig. 8 is a transverse section of the same. Fig. 9 is a perspective view of the endless belt of leather as used upon the strops illustrated in Figs. 4, 5, and 6; and Fig. 40 10 is a perspective view of the belt-fastening for uniting the two ends of the leather strap to form an endless belt.

In the construction of my improved strops I first form a tube, *a*, of the desired cross-section, according to the style of strop to be made, of tin or other thin sheet metal, and of any desired length, according to the length of strop desired. I then fit to the interior of said tube

two blocks, *b* and *b'*, of wood of different lengths, each provided at one end with one or 50 two lips or beads, *b*², to form supports for the leather strap *c*.

In the strop illustrated in Figs. 1 and 2 the tube *a* is made three-cornered, and in the strops of which Figs. 3, 4, and 6 are sections 55 55 the tubes *a* are rectangular, but of different proportions, according to the style of strop to be made. In each case one of the blocks of wood, preferably the longest one, *b'*, is permanently secured to the tube *a*.

A is the strop-handle mounted upon and secured to the screw-shank *d*, as set forth and described in another application of mine now pending in the Patent Office at Washington, filed March 19, 1883. The shank or screw-65 rod *d* has formed thereon two pairs of radially-projecting wings or flanges, *d'* and *d*², arranged at a distance apart equal to the length of the wooden block *b* plus the thickness of the washer *e*, mounted upon said shank, and 70 the thickness of the leather strap *c*. The washer *e* is slipped on the screw-rod *d* before one pair at least of the wings or flanges is formed thereon, and said rod has cut thereon a male screw-thread to fit and work in the 75 nut *f*, as shown in Fig. 1. The wooden block *b* has a hole bored longitudinally through it of a diameter corresponding to the diameter of the screw rod or shank *d*, and the block *b'* has a corresponding hole bored into its inner 80 end, in line with the hole in the block *b*, to a sufficient depth to receive that part of the rod *d* which projects beyond the wings or flanges *d'*.

When the rod *d* is completed, with washer *e* thereon, and the wings *d'* and *d*² formed and the screw-thread cut thereon, the unthreaded end, with the wings or flanges *d'*, is driven through the block *b* till the washer *e* comes in contact with the inner end of said block and the flanges *d*² are in contact with said washer, 90 when the handle *A* is driven upon the unthreaded end of said rod till the end of its ferrule *g* comes in contact with the leather strap *c*, one end of which has previously been secured to the outer end of the block *b* by 95 tacks, as shown, or in any other suitable man-

ner. The nut *f* is then screwed upon the threaded end of the rod *d* till it comes in contact with the wings or flanges *d*², when the block *b* is slipped into the tube *a* till the nut *f* comes in contact with the inner end of the block *b'*, and the leather strap *c* is drawn taut over the lip *b*² on the block *b'* and secured thereto by tacks, as shown in Fig. 1. This description of the manner of applying the leather strap is applicable to all forms of my improved strop in which only one leather surface is used; but in case two leather surfaces are desired the leather strap has its two ends united by the clasp or fastener *h*, provided 15 with the two series of prongs *h'*, which pierce the leather, and are clinched down upon the inside of the strap, and between it and the end of the block *b* or *b'*, as shown in Fig. 5. The strap *c* has an opening punched through it at 20 the center of its length, or so as to be directly opposite the clasp *h*, as shown at *i*, Fig. 9; or said hole may be made through the center of the clasp *h*, if desired, said hole being for the passage of the rod *d* at the handle end of the 25 strop, which is passed through said opening before the handle *A* is driven upon the rod *d*; and when the block *b* has been slipped into the tube *a* to its greatest depth the other end of the looped strap is slipped over the outer 30 end of the block *b'*, when it is strained by turning the handle *A* and screw-rod *d*, and requires no other fastening. The two exterior surfaces of the tube *a* not covered by the leather strap *c* in the strops illustrated by 35 Figs. 1, 2, and 4, and the surface of said tube that is opposite to the leather strap *c* in Fig. 3, are covered with a covering of thin leather, upon which is spread a coating of emery and oil of different degrees of fineness when there is 40 more than one such surface, said different degrees of fineness being indicated by different colors in a well-known manner.

The washer *e* and nut *f* are made of such a shape that they cannot revolve within the tube 45 *a*, and the wings or flanges *d*² simply serve to form a shoulder to bear against the washer *e* and confine the block *b* between it and the end of the handle; and therefore a circumferential collar formed on the rod *d* in place of said 50 wings would be equally effective; and hence I do not wish to be confined to the particular form of the shoulder or projection shown.

It is very desirable to have a hone-surface composed of emery and glue or other suitable 55 adhesive material, for use when the razor is very dull, and it is also very desirable that the fine finishing-surface of the leather strap should be kept clean and free from grit. To attain both of these desirable ends, I apply a cover 60 or tablet, *j*, made from sheet metal, and having lips *j'* turned at right angles to the main body thereof along its two sides, to the strop, in such a manner as to cover said leather strap, as shown in Figs. 1, 2, 3, and 4, and cover its 65 outer surface with a coating of emery and glue, which forms a good hone-surface. The cover

or tablet *j* has an ear or flange, *j*², turned at right angles thereto at one end, in which is formed a slot, *j*³, which engages with the screw-stud or knob *k*, set in the outer end of the block *b'*, 70 as shown in Fig. 1, which prevents the tablet from moving endwise when stropping a razor. In the strop shown in Figs. 5 and 6 the tube *a* has built therewith or secured thereto one or more rectangular boxes for holding razors, 75 brushes, or other articles, and in this case I pivot the tablet *j*, by the end opposite to the ear *j*², to the sides of said box or boxes, to serve as a cover thereto, and also as a hone, the slot in the ear *j*² embracing the pin *l* when the cover 80 is closed.

One advantage of the use of my invention is the greatly-increased capacity of the strop, due to the use of the tablet or cover *j*, and another is that the inner end of the handle *A* is always 85 in contact with the end of the strop instead of being removed from it, when the strap is new, so as to expose the screw-shank, as heretofore practiced, the mechanism for straining the leather strap in my strop being all out of sight 90 within the metal tube *a*.

The tablet *j* may be covered with leather and a coating of emery and oil, instead of the hone-surface of glue and emery, and it may be used for covering the finely-finished surface 95 of the leather strap *c*, for covering another hone-surface, or for covering a box or receptacle for the razor, brush, or other article. It may also be used with equal utility for covering a finely-finished russet-leather surface directly upon the surface of the body of the strop, as in strops that have only two working 100 sides, like the so-called "Emerson Strop."

All of the different forms of my improved strop are provided with cases (not shown) of 105 ordinary construction, which inclose the body of the strop, including the tablets or covers.

The clasp *h* makes a very effective fastening for uniting the ends of the belt *c*, when located so that its clinches are in contact with the end 110 of the block *b* or *b'*, so that the clinched prongs cannot be straightened out by the strain on the belt.

What I claim as new, and desire to secure by Letters Patent of the United States, is— 115

1. In a razor-strop, the combination of the tube *a*, the movable block *b*, the fixed block *b'*, the leather strap *c*, the handle-operated screw *d*, and the nut *f*, all arranged and adapted to operate substantially as and for the purposes described. 120

2. In combination with a razor-strop, the cover or tablet *j*, having a hone or other razor-sharpening surface thereon, and arranged to be removed therefrom, substantially as described. 125

3. The combination, in a razor-strop, of a metal tube, *a*, a fixed block, *b'*, a movable block, *b*, the handle-operated screw *d*, nut *f*, one or more boxes or receptacles formed upon 130 or secured to the side or sides of the tube *a*, and one or more hone-tablets pivoted thereto,

all arranged and adapted to operate substantially as and for the purposes described.

4. The combination of the strop frame or tube *a*, the fixed block *b*', the movable block *b*,
5 the handle-operated screw *d*, nut *f*, and the continuous belt *c*, having its ends secured together by the clasp *h*, clinched upon the inside of said belt, and arranged with said clinches bearing against the end of one of the blocks *b* or *b*',
10 substantially as described.

In testimony whereof I have signed my name to this specification, in the presence of two subscribing witnesses, on this 15th day of May, A. D. 1883.

SIGOURNEY WALES.
